United States Patent Office

Des. 222,337
Patented Oct. 19, 1971

222,337

BOTTLE

Richard L. Weckman, Perrysburg, Ohio, assignor to Owens-Illinois, Inc., Toledo, Ohio

Filed Sept. 8, 1970, Ser. No. 24,886

Term of patent 14 years

Int. Cl. D9—01

U.S. Cl. D9—115

FIG. 1

FIG. 3

FIG. 2

FIG. 4

FIG. 1 is a perspective view of a bottle showing my new design;

FIG. 2 is a front elevational view of a bottle showing my new design, the opposite side being the same in appearance as the side shown;

FIG. 3 is a top plan view; and

FIG. 4 is a side elevational view, the opposite side being the same in appearance as the side shown.

I claim:

The ornamental design for a bottle, substantially as shown and described.
